Inventor
Paul W. Amstie,
By S. Brandton
his Attorney

UNITED STATES PATENT OFFICE.

PAUL W. AMLIE, OF COOPERSTOWN, NORTH DAKOTA.

HOPPLE.

SPECIFICATION forming part of Letters Patent No. 627,040, dated June 13, 1899.

Application filed May 26, 1898. Serial No. 681,852. (No model.)

To all whom it may concern:

Be it known that I, PAUL W. AMLIE, a citizen of the United States, residing at Coopers-
town, in the county of Griggs and State of
5 North Dakota, have invented certain new and
useful Improvements in Hopples, of which the
following is a specification, reference being
had therein to the accompanying drawings.

My invention relates to hopples for animals;
10 and its object is to provide a device of this
character which will be inexpensive to manu-
facture and strong and durable in use and
may be easily applied to and removed from
the animal's legs.

15 The invention consists in the features of
construction and combinations of devices
hereinafter fully described, and illustrated in
the accompanying drawings, in which—

Figure 1 is a perspective view of a hopple
20 embodying the invention, and Fig. 2 is a sectional view.

The hopple consists of two counterpart mem-
bers A and B, each comprising a stem or shank
25 a and a loop or band formed of two sections
b and c, hinged together at the point d. The
section b of the band is formed integral with
the stem or shank a, and the free end of the
30 section c is bent inwardly to form a catch e,
adapted to engage a lug or projection f on the
stem or shank a. The hinged section c after
engaging the lug f is secured in such engage-
ment by a slide g, arranged on the stem and
35 secured to one end of a spring h, which is
coiled around the stem and secured at its op-
posite end thereto, as shown at i.

It is obvious that the tendency of the spring
h is to force the slide g toward the band or
loop, and hence said spring serves to retain
40 said slide in position over the end of the band-
section c to hold the latter in engagement with
the lug f.

To disconnect the section c from the stem,
so that said section may be turned on its hinge
to remove the band from the animal, it is only
necessary to grasp the slide g with the fingers 45
and force it along the stem against the tension
of the spring until the end of the section c is
free.

The two bands or loops are connected by
links k, connected together at their ends l and 50
secured at their opposite ends m to the bands,
as shown.

The bands are preferably made of metal,
although I of course do not restrict myself to
any particular material in their construction. 55

Having thus fully described my invention,
what I claim is—

A hopple for animals consisting of two con-
nected counterpart sections, each comprising
a stem provided with a projecting lug, and a 60
band or loop formed of two hinged sections,
one of said sections being integral with the
stem while the other section is bent at its free
end to form a catch adapted to engage the lug
on the stem, in combination with a slide ar- 65
ranged on the stem and a coil-spring sur-
rounding the stem and secured at one end to
the slide, and at its opposite end to the stem
said spring being adapted to be compressed
by the movement of the slide to release the 70
sections and to automatically force the slide
back to lock the sections when the slide is re-
leased.

In testimony whereof I affix my signature
in presence of two witnesses.

PAUL W. AMLIE.
